UNITED STATES PATENT OFFICE.

ROBERT S. MILLER, OF CLEVELAND, OHIO.

CAR-DOOR FASTENING.

1,092,939.

Specification of Letters Patent. Patented Apr. 14, 1914.

Application filed January 16, 1914. Serial No. 812,447.

To all whom it may concern:

Be it known that I, ROBERT S. MILLER, a citizen of the United States, residing at Cleveland, in the county of Cuyahoga and State of Ohio, have invented certain new and useful Improvements in Car-Door Fastenings, of which the following is a specification.

The invention relates to car door fastenings of the type ordinarily employed with seals for indicating the unauthorized opening of the doors. The invention has for its primary objects, the provision of an improved construction wherein the withdrawal of the bolt without breaking the sealing wire or band is rendered impossible, and the provision of an improved stop construction for preventing the entire withdrawal of the bolt from the guide. One embodiment of the invention is illustrated in the accompanying drawing, wherein—

Figure 1 is a front elevation of a door provided with my improved fastener, Fig. 2 is a horizontal section through the door, 25 showing the fastening in plan view, and Figs. 3 and 4 are sections on the lines III—III and IV—IV respectively, of Fig. 1, Fig. 4 being on an enlarged scale.

Referring to the general arrangement of parts as illustrated in Figs. 1 and 2, 1 is the slide door; 2 is the post; 3 is the door stop; 4 is the staple secured to the slide door and carrying the usual hasp 5 slotted at its end as indicated at 6 (Fig. 1); 7 is a plate secured rigidly against the face of the door stop 3 and provided with the loop 8 over which the hasp 5 fits, and with the socket 9 for receiving the bolt; and 10 is the bolt which fits slidably through the socket 9 and the loop 8. My invention relates principally to the socket and bolt construction, the general arrangement of parts being otherwise old and well known in the art.

As indicated in Fig. 4, the opposite walls of the socket member 9 are perforated as indicated at 11 and 12, in order to receive the sealing band or wire. As also indicated in Fig. 4 the bolt 10 is made in U form in cross section, with the opposing walls thereof perforated as indicated at 13 and 14, such perforations being in alignment with the perforations 11 and 12 when the bolt is in its locking position as indicated in Figs. 1 and 3. In order to prevent the withdrawal of the bolt the metal band 15 is employed, carrying the usual lead seal 16.

Fitting up inside the bolt to the rear of the perforations and sealing strip when the bolt is in locking position as indicated in Fig. 3, is the lug 17.

The provision of this lug 17 is important, as it eliminates the possibility of the bolt being moved to unlocked position, without breaking the seal. It will be seen that in order to move the bolt to unlocked position while the sealing band is in position it would be necessary to draw two thicknesses of the band or wire to the rear on each side of the bolt. For instance taking one side of the bolt, one thickness of the band or wire would have to be drawn into the space between the outer face of the bolt and the inner wall of the socket, and the other length of the band of wire would be drawn between the inner face of the bolt and the surface of the lug 17. Even with the bolt having a relatively loose fit in the socket this is practically impossible, even with a very fine sealing wire, since the spaces between the walls of the socket and the bolt, and between the bolt and lug are not sufficient to accommodate these many thicknesses of wire, and the plurality of bends thus made in the wire or band prevent its slipping longitudinally, so that any attempt to move the bolt to the rear while the wire or band is in position will shear such wire or band, thus indicating the unauthorized tampering with the fastening.

The distinction in this construction over the ordinary construction in which a solid bolt is used, will be readily understood when it is considered that with such a construction the movement of the bolt to the rear will pull only two thicknesses of wire between the inner surface of the socket and the outer surface of the bolt, and it is frequently possible, particularly where a wire is used, to pull the bolt to the rear sufficiently to permit the unlocking of the door, without breaking the wire or injuring the seal. It will be seen that with my invention the number of thicknesses of wire which have to be crowded between the opposing surfaces is doubled, thus practically eliminating all possibility of the opening of the car without breaking the wire.

In order to prevent the bolt from being entirely withdrawn from the socket 9, the side edges at the end of the bolt are extended as indicated at 18 (Figs. 1 and 3), and after the bolt has been inserted through the socket 9 these edges 18 are turned in, the bolt

being of malleable metal. When the bolt is moved outward and approaches its extreme outer position these inturned edges 18 will engage the lug 19 formed on the bottom of 5 the socket adjacent the lug 17. The lug 17 would also accomplish this function, but it is desirable to stop the movement of the bolt before it reaches a position as far out as this, so that the lug 19 is formed in advance of the lug 17, for performing this 10 function. Other advantages incident to the tightness and cheapness of the structure will be readily apparent to those skilled in the art.

15 What I claim is:

1. In combination in a door fastening, a socket member provided with a pair of opposing perforated walls and a lug lying between the said walls and spaced away 20 therefrom, and a bolt comprising a pair of opposing connected perforated plates fitting slidably between the said walls of the socket member with their edges lying between the said walls and the sides of the lug, the said 25 perforations in the bolt lying in alinement with those of the socket member and in advance of the lug when the bolt is in its forward or locking position.

2. In combination in a door fastening, 30 a socket member provided with a pair of opposing perforated walls and a lug lying between the said walls and spaced away therefrom, and a hollow bolt U-shaped in cross section fitting slidably in the socket between 35 the said walls of the socket member and having its walls perforated with their edges lying between the sides of the said lug and the walls of the socket member, the said perforations in the bolt lying in alinement 40 with those in the socket member and in advance of the said lug when the bolt is in its forward position.

3. In combination in a door fastening, 45 a socket member provided with a pair of opposing perforated walls and a lug lying between the said walls and spaced away therefrom, and a bolt comprising a pair of opposing connected perforated plates fitting slidably between the said walls of the socket 50 member with their edges lying between the

said walls and the sides of the lug, the said perforations in the bolt lying in alinement with those of the socket member when the bolt is in its forward position, and the forward ends of the said plates being bent inward to engage the said lug when the bolt is moved to the rear and thus prevent the complete withdrawal of the bolt from the socket member.

4. In combination in a door fastening, 60 a socket member provided with a pair of opposing perforated walls and a lug lying between the said walls and spaced away therefrom, and a bolt comprising a pair of opposing connected perforated plates fitting slidably between the said walls of the socket member with their edges lying between the said walls and the sides of the lug, the said perforations in the bolt lying in alinement with those of the socket member when the 70 bolt is in its forward position, and the forward end of one of said plates being bent in so as to engage the said lug when the bolt is moved to the rear, thus preventing the complete withdrawal of the bolt from the 75 socket member.

5. In combination in a door fastening, a socket member provided with a pair of opposing perforated walls and a lug lying between the said walls and spaced away therefrom, and a hollow bolt U-shaped in cross section fitting slidably in the socket between the said walls of the socket member and having its walls perforated with their edges lying between the sides of the 85 said lug and the walls of the socket member, the said perforations in the bolt lying in alinement with those in the socket member and the forward end of the bolt being bent in so as to engage the said lug when the bolt 90 is moved to the rear, thus preventing the complete withdrawal of the bolt from the socket member.

In testimony whereof I have hereunto signed my name in the presence of the two 95 subscribed witnesses.

ROBERT S. MILLER.
